BARBER'S COMB

Henry E. Mandato, Goshen, N. Y.

Application September 20, 1950, Serial No. 185,767

3 Claims. (Cl. 132—11)

1

My invention relates to combs and in particular to combs used by professional barbers.

Heretofore various shaped combs have been used in an attempt to cut the hair in the contour of the head, but these attempts have been unsuccessful because of the tendency of the hair to fall naturally into place and thus lie closely along the comb or return to position on the head by slipping through the comb teeth.

One of the objects of my invention is to provide a comb shaped so that its teeth fit snugly against the contours of the human body; yet which forces the hairs away from the head corresponding to the contours over which the hair lies.

Another object of my invention is to provide a means of forcing the hair to stand out through the teeth of the contour comb in such a manner that these hairs may be uniformly cut.

Another object of my invention is to provide a comb and bar for forcing the hair into contour alignment of such construction that they may be used together or the comb may be used alone.

Other objects and advantages will be apparent from the specification and drawings, in which—

Fig. 1 is a side view of the comb and bar in position for use;

Fig. 2 is a top section of the comb and bar taken along the line 2—2 of Fig. 1 and showing the bar in dotted line non-operating position;

Fig. 3 is an end section of the comb and bar taken along the line 3—3 of Fig. 1 showing the bar in primary position;

Fig. 4 is an end section of the comb and bar along line 3—3 of Fig. 1 showing the bar in secondary or operational position.

Referring to the drawings, 1 is the handle of the comb, which may be of any desired shape, 2 are the comb teeth which are attached to the base 3 in any desired manner or are formed as a part of the base as is usually the case with combs made of synthetic resins. The teeth 2 are moulded into a triangular shape, starting sharply at the bottom, and are bent outwardly slightly intermediate their ends as shown at 4 ending in a tapered portion 5 so that the ends 5 of the teeth 2 are offset angularly from the base 3.

In any convenient location near the teeth 2 is an orifice 6 through which passes a rod 7 made of any suitable material, preferably steel. This rod has attached to its end a thumb rest 8 in the form of a disc with serrations 9, the serrations being provided for a better gripping surface. Between the thumb disc 8 and the comb handle 1 is a tension means, preferably a spring 10 which

5 is held from horizontal displacement by surrounding the rod 7 and from vertical displacement by being contained by the thumb disc 8 and a retaining washer 11 which abuts on the comb handle 1.

10 After the rod 7 passes through the orifice 6 it is bent twice to form a gooseneck as at 12 so that the rod 7 is at right angles to its shank and offset from the handle 1 forming a bar 12 which in normal operation extends along the base of the comb teeth 2, and in out of use operation extends along the side of the handle 1 as shown in the dotted line position of Fig. 2.

15 In operation, the handle is grasped with the hand and the comb teeth 2 run through the hair, the ends of the teeth 5 running close to the scalp. When sufficient hair has entered the teeth of the comb, the wrist of the operator is turned so that the base of the teeth rest against the scalp and the ends 5 now are separated slightly from the scalp because of the rectangular bulge 4 and outward bend 5 of the teeth ends. The operator depresses the thumb disc 8 against the force of the spring 10 thus lifting the bar 12 along one 20 side of the comb and forcing the hair to stand sharply outward through the comb teeth where they may be readily and uniformly cut. After cutting the hair thumb disc 8 may be released whereby the tension means 10 returns the bar 12 to a position at the base of the teeth 2.

25 If the operator does not desire to use the bar 12 the thumb disc 8 may be rotated 180° thus placing the bar 12 in a position along the handle 1 as shown by the dotted line position of Fig. 2.

30 What I claim is:

35 1. A hair cutting comb comprising, a base having tapered teeth projecting therefrom, said teeth being bent intermediate of their ends and extending angularly with respect to said base, a bar extending longitudinally of and in abutment with said teeth, said bar connected to said base and held normally against the base of said teeth by tension means, and movable over one side of said teeth against said tension means.

40 2. A hair cutting comb comprising, a base having tapered teeth projecting therefrom, said teeth being bent intermediate of their ends and extending angularly with respect to said base, a bar extending longitudinally of and in abutment with said teeth, said bar connected to said base in swiveled relationship and held normally against the base of said teeth by spring tension means, and movable over one side of said teeth against said tension means.

45 3. A hair cutting comb comprising, a base

having tapered and outwardly bent teeth projecting therefrom, said teeth being bent intermediate of their ends and extending angularly with respect to said base, a bar extending longitudinally of said teeth, said bar connected to said base in swiveled relationship and held normally against the base of said teeth by tension means and movable over one side of said teeth against said tension means, and a finger operable means connected to said bar, whereby said bar may be 10 swiveled into or out of proximity with said teeth.

HENRY E. MANDATO.
